UNITED STATES PATENT OFFICE.

FRED LOBNITZ, OF CROOKSTON, SCOTLAND.

NAVIGABLE ROCK-CUTTER.

1,018,917.

Specification of Letters Patent. Patented Feb. 27, 1912.

Application filed July 17, 1911. Serial No. 638,835.

To all whom it may concern:

Be it known that I, FRED LOBNITZ, a subject of the King of Great Britain, residing at Crookston, Renfrewshire, Scotland, have 5 invented certain new and useful Improvements in Navigable Rock-Cutters, of which the following is a specification.

This invention relates to navigable rock cutters, that is to say, to vessels adapted to 10 steam from place to place as required and which carry a rock breaking or cutting apparatus of the well known "Lobnitz" type. Under this invention the steam vessel is made with a well at the bow and another 15 well amidships so that the rock cutter (or cutters) can be operated either from the midship position or the bow position, a single structure being used for carrying the rock cutter in either position. The structure 20 consists of a tripod arrangement of sheer legs, the central leg of the tripod being articulated at its upper end to the other two legs which latter can be moved from the one position to the other position preferably upon the central leg as a pivot. All 25 three legs are secured at their lower ends to bracket shoes suitably arranged on the deck.

In order that the invention may be clearly understood I have hereunto appended explanatory sheets of drawings, whereon:—

Figure 1 shows a navigable vessel propelled by a steam power. Fig. 2 is a plan thereof, and Fig. 3 a cross section on the line X—X.

As will be seen from the drawings the vessel A is made with a central well b and a well c in the bow. The central well is shown as provided with an ordinary cutter guide d through the hole in the center of 35 which the heavy metal rock cutter e works this cutter being raised and dropped by means of the wire rope f and winch g.

The structure B consists of three legs h, i, j, the two legs h, i, being rigidly bound 40 together at the top and carrying the guide pulley h for the wire rope. The central leg j is jointed at its upper end to the legs h, i, by means of a strong pivot bolt l. The three legs at their lower ends are secured to 45 bracket shoes m, n, n¹, by bolts. As will be seen in plan at Fig. 2 there are five shoes, one m in the center, two n, n¹, amidships and two o, o¹, at the bow and the sheer legs h, i, can be secured either to the shoes n, n¹, 50 or to the shoes o, o¹, the third leg always remaining pivotally secured to the central

bracket shoe m. In some cases the side legs may have bracket shoe adapted to slide in guides on the deck (as indicated in dotted lines at z Fig. 2) the shoes being secured by 60 bolts in either position as desired.

The legs, when secured in either the bow position as shown in dotted lines at Fig. 1, or the midship position as shown in full lines at Fig. 1, can be bound together by 65 girders p. A platform q is carried by the legs h, i. When it is necessary to work at the bow of the boat the front well is provided with a cutter guide r similar to that shown at d, this guide being held in position 70 by means of a cross girder t which also serves to bind the two parts of the bow together. When the legs h, i, are to be shifted from the shoes n, n¹, to the shoes o, o¹, the bracing girders are removed.

The navigable vessel is built so as to work 75 in a heavy sea.

In order that the operation of the rock cutter can be controlled from the bridge the lever u of the winch clutch is connected 80 by a chain v (or rods) to a hand lever w on the bridge so that by operating said hand lever the winch drum can be clutched to its shaft or released as desired. The clutch lever u can be retracted by a spring x.

Having now fully described my invention what I claim and desire to secure by Letters Patent is:—

1. A navigable rock cutter comprising, in combination, a vessel having a well at the 90 bow and a well amidships, a rock cutter, a structure located between said wells and having a pivotal member upon which it can be moved from the one well to the other in order to carry the cutter either at the bow or 95 amidships, and means for operating the cutter.

2. A navigable rock cutter comprising, in combination, a vessel having a well at the 100 bow and a well amidships, a rock cutter, a tripod structure located between said wells and having a pivotal member upon which it can be moved from the one well to the other in order to carry the cutter either at the bow or amidships and means for operating the cutter.

3. A navigable rock cutter comprising, in combination, a vessel having a well at the 110 bow and a well amidships, a rock cutter, means for operating the cutter, a movable tripod structure comprising two side members and an intermediate third member

jointed at its upper end thereto and also jointed to the deck of the vessel, the side members being adapted to swing on the intermediate member into position either 5 at the bow or amidships.

4. A navigable rock cutter comprising, in combination, a vessel having a well at the bow and a well amidships, a rock cutter, a movable tripod structure comprising two 10 side members and an intermediate third member jointed at its upper end thereto, a set of shoes for securing the side members amidships, a second set of shoes for securing the side members at the bow and an intermediate shoe to which the third member is 15 pivoted the structure being adapted to carry the cutter either at the bow or amidships, and means for operating the cutter.

5. A navigable rock cutter comprising, in

combination, a vessel having a well at the 20 bow and a well amidships, a rock cutter, a pair of sheer legs having means for carrying the cutter, means on the deck and adjacent to the well at the bow for the attachment to the deck of the said sheer legs, 25 means on the deck and adjacent to the well amidships for the attachment to the deck of the said sheer legs, and a third leg pivotally secured to the deck between the wells for supporting the pair of legs either at the 30 bow or amidships.

In testimony whereof I affix my signature in presence of two witnesses.

FRED LOBNITZ.
